(57) **CLAIM**

The ornamental design for a beverage cartridge, as shown and described.

DESCRIPTION

FIG. 1 is a top, front, left perspective view of a beverage cartridge showing a first embodiment of our new design;
FIG. 2 is a left side elevational view thereof;
FIG. 3 is a right side elevational view thereof;
FIG. 4 is a rear elevational view thereof;
FIG. 5 is a front elevational view thereof;
FIG. 6 is a top plan view thereof;
FIG. 7 is a bottom plan view thereof;
FIG. 8 is top, rear, left side perspective view thereof;
FIG. 9 is a top, front, left perspective view of a second embodiment thereof;
FIG. 10 is a left side elevational view of FIG. 9;
FIG. 11 is a right side elevational view of FIG. 9;
FIG. 12 is a rear elevational view of FIG. 9;
FIG. 13 is a front elevational view of FIG. 9;
FIG. 14 is a top plan view of FIG. 9;
FIG. 15 is a bottom plan view of FIG. 9; and,
FIG. 16 is top, rear, left side perspective view of FIG. 9.
In the drawings, the dash-dot-dash broken lines define the
claim boundaries and form no part of the claimed design. The
dash-dash broken lines are for the purpose of illustrating
environment only and form no part of the claimed design.

1 Claim, 12 Drawing Sheets
